Attn: Attorney

ing and closing. Preferably handles 47 and 48 are positioned in the paths of latch members 41 and 42 and prevent the latch members from being fully opened, as shown at the left in Figure 1. Therefore, the latch members ordinarily drop into engagement with keepers 43 and 44 when they are not held open.

From the construction described, it is seen that I have provided a tuyère shield which is supported at the furnace wall with its peripheral edges in engagement with the tuyère jacket. Thus the shield leaves no space for matter to escape around its edges. The shield is securely locked in place normally, but is supported for easy sliding movement to furnish access to the tuyère mechanism.

While I have shown but a single embodiment of the present invention, it is apparent that modifications may arise. Therefore I do not wish to be limited by the disclosure set forth, but only by the scope of the appended claims.

I claim:

1. In combination with a blast furnace, a tuyère shield comprising a pair of doors slidably mounted at the exterior of the furnace wall and in closed position surrounding the tuyère pipe, the outer peripheral edges of said shield engaging the wall to close off the tuyère opening against escape of material on tuyère failure, said doors opening by sliding movement in opposite directions away from the tuyère pipe.

2. In combination with a blast furnace, a tuyère shield comprising a pair of doors slidably mounted at the exterior of the furnace wall and having mating recesses in their inner edges adapted to receive the tuyère pipe and additional recesses adapted to receive coolant pipes, said doors in closed position surrounding the tuyère pipe, said doors opening by sliding movement in opposite directions away from the tuyère pipe.

3. In combination with a blast furnace, a tuyère shield comprising a pair of doors slidably mounted at the exterior of the furnace wall and in closed position surrounding the tuyère pipe, and releasable means for locking said doors in closed position, the outer peripheral edges of said shield engaging the wall to close off the tuyère opening against escape of material on tuyère failure, said doors opening by sliding movement in opposite directions away from the tuyère pipe.

4. In combination with a blast furnace, tuyère shield comprising a pair of doors slidably mounted on the tuyère jacket at the exterior of the furnace wall and in closed position surrounding the tuyère pipe, and releasable means for locking said doors in closed position, said doors opening by sliding movement in opposite directions away from the tuyère pipe.

5. In combination with a blast furnace, a tuyère shield comprising a pair of doors slidably mounted

on the tuyère jacket at the exterior of the furnace wall, and releasable means for locking said doors in closed position, said doors having mating edge recesses adapted to receive the tuyère pipe and passages to receive coolant pipes, said doors opening by sliding movement in opposite directions away from the tuyère pipe.

6. In combination with a blast furnace, a tuyère shield comprising a pair of doors slidably mounted on the tuyère jacket at the exterior of the furnace wall, releasable means for locking said doors in closed position to the jacket, said doors having mating edge recesses adapted to receive the tuyère pipe, additional recesses adapted to receive coolant pipes, and passages adapted to receive water spray pipes, said doors opening by sliding movement in opposite directions away from the tuyère pipe.

7. In combination with a blast furnace, a tuyère shield comprising a pair of doors slidably mounted on the tuyère jacket at the exterior of the furnace wall, releasable means for locking said doors in closed position to the jacket, said doors having mating edge recesses adapted to receive the tuyère pipe, additional recesses adapted to receive coolant pipes, and passages adapted to receive water spray pipes, latch bars on said doors cooperable with the water spray pipes, and keepers on said doors for receiving said latch bars.

8. In combination with a blast furnace, a tuyère shield comprising a pair of doors slidably mounted on the tuyère jacket at the exterior of the furnace wall, releasable means for locking said doors in closed position to the jacket, said doors having mating edge recesses adapted to receive the tuyère pipe, additional recesses adapted to receive coolant pipes, and passages adapted to receive water spray pipes, latch bars on said doors cooperable with the water spray pipes, keepers on said doors for receiving said latch bars and handles on said doors to facilitate their operation and being cooperable with said latch bars to engage the latter automatically with said keepers.

EARL C. MILLER.
